[57] CLAIM

We claim the ornamental design for a media holder, as shown and described.

DESCRIPTION

FIG. 1 is a upper right frontal perspective view, with exemplary media that are boxes for holding compact disks shown in phantom lines, of the media holder comprising the present invention;

FIG. 2 is a upper right frontal perspective view thereof;

FIG. 3 is a front elevational view thereof;

FIG. 4 is a right side elevational view thereof, and the left side is a mirror image thereof;

FIG. 5 is a rear elevational view thereof;

FIG. 6 is a top plan view thereof; and,

FIG. 7 is a bottom plan view thereof.

The broken line showings of compact disc boxes in FIG. 1 are for illustrative purposes only and form no part of the claimed design.
